COMBINED ASH TRAY AND CIGARETTE HOLDER OR SIMILAR ARTICLE

Adam Kurant, Youngstown, Ohio

Application May 14, 1954, Serial No. 30,495

Term of patent 7 years

(Cl. D85—2)

To all whom it may concern:

Be it known that I, Adam Kurant, a citizen of the United States, residing at Youngstown, in the county of Mahoning and State of Ohio, have invented a new, original, and ornamental Design for a Combined Ash Tray and Cigarette Holder or Similar Article, of which the following is a specification, reference being had to the accompanying drawing forming a part thereof.

The figure is a perspective view of a combined ash tray and cigarette holder or similar article, showing my new design.

I claim:

The ornamental design for a combined ash tray and cigarette holder or similar article, as shown.
